[57] CLAIM

The ornamental design for a plant support system, as shown and described.

DESCRIPTION

FIG. 1 is a perspective view of a plant support system embodying the present invention;

FIG. 2 is a top plan view thereof;

FIG. 3 is a bottom view thereof;

FIG. 4 is a front view thereof;

FIG. 5 is a rear view thereof;

FIG. 6 is a side view thereof; and,

FIG. 7 is a left side view thereof.

The portion of the ground into which the end portion of the support post is inserted, shown in broken lines, is not intended to be part of the claimed invention.
